UNITED STATES PATENT OFFICE.

VICTOR A. DE PROSSE, OF SAN FRANCISCO, CALIFORNIA.

DESIGN FOR A CHRISTMAS-TREE ORNAMENT.

SPECIFICATION forming part of Design No. 24,923, dated November 26, 1895

Application filed August 29, 1895. Serial No. 560,937. Term of patent 7 years.

To all whom it may concern:

Be it known that I, VICTOR A. DE PROSSE, of San Francisco, in the county of San Francisco and State of California, have invented a new and original Design for a Christmas-Tree Decoration, of which the following is a full, clear, and exact description.

Reference is to be had to the accompanying drawing, which is a perspective view of a decoration for Christmas-trees embodying my new and original design.

The leading feature of the design consists in the decoration made to represent a conventional flower or lily.

This decoration, as herein shown, comprises 15 an upper conical figure A, representing the perianth or calyx, having serrations B, representing the sepal, a figure C, representing the stem, and elongated figures D appearing as depending from the upper portion and representing the stamens of the lily.

I claim—

The design for a Christmas tree decoration, herein shown and described.

VICTOR A. DE PROSSE.
